DESIGN FOR A COMBINED MICROPHONE AND HAND CONTROL DEVICE FOR A PHONOGRAPH

William J. O'Neil, Atlantic Beach, N. Y., assignor
to Dictaphone Corporation, New York, N. Y., a
corporation of New York

Application March 13, 1942, Serial No. 106,195

Term of patent 14 years

To all whom it may concern:

Be it known that I, William J. O'Neil, a citizen of the United States and a resident of Atlantic Beach, in the county of Nassau and the State of New York, have invented a new, original, and ornamental Design for a Combined Microphone and Hand Control Device for a Phonograph, of which the following is the specification, reference being had to the accompanying drawing, forming part thereof.

Figure 1 is a perspective view, taken from

above, of the right-hand side and front of a combined microphone and hand control device for a phonograph, showing my new design.

Figure 2 is a similar perspective view of the left-hand side and back of the same.

I claim:

The ornamental design for a combined microphone and hand control device for a phonograph, substantially as shown.

WILLIAM J. O'NEILL.
